(57) **CLAIM**

The ornamental design for a cooking appliance handle as shown and described.

DESCRIPTION

FIG. 1 is a perspective view of a cooking appliance handle showing the new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof; and,

FIG. 8 is a perspective view of a cooking appliance with a cooking appliance handle of the new design.

The broken lines are for environmental purposes only and do not form any part of the claimed design.

1 Claim, 4 Drawing Sheets(56)
